Application May 9, 1956, Serial No. 583,669

Claims priority, application Germany May 12, 1955

11 Claims. (Cl. 315—3.5)

The invention relates to the electrode structure for a traveling wave tube having a delay line built up as a helix.

With the well known traveling wave tubes of this kind, the wire helix, serving as a delay line, is embedded between at least three ceramic rods serving to support the helix line. That is because the helix line is generally made from a relatively thin wire which does not ensure the necessary stiffness of the helix. The assembling of the tube system is hereby done—as is for instance clearly shown in Fig. 1 of the French patent specification 954,964—in a way that the ceramic rods together with the helix are pushed into a gaged glass tube into which there are likewise pushed corresponding structural parts of the electron gun as well as the electron catcher of the tube. With said well known arrangement, the helix line together with its supporting means, therefore, forms a structural part separate from both the electron gun and the electron catcher. Moreover, this kind of helix support requires a most exactly calibrated glass tube. This will be extremely difficult if the tube is to be operated with very short waves at which the helix line has a diameter of only a few millimeters. Consequently, even the dimensions of the other parts of the tube, such as those of the calibrated glass envelope, of the electron gun system, etc., will at the same time decrease. Said well known structure has been put into practice only with traveling wave tubes to be operated with relatively longer waves. Therefore, another method has already been used as for instance shown in the journal "Die Telefunken-Röhre," No. 32, page 4, Fig. 1, consisting in the fact that the cage of the helix line support, formed by the ceramic rods, is maintained, whereby said cage in itself is self-supporting. In order to obtain a proper location of the axis of the electron gun with respect to that of the helix line, there is, with said well known arrangement, provided a further cage of ceramic rods into which both the electron gun and the cage of the helix line support are built. Thus, there is obtained a rigid structural unit which can be assembled and adjusted as a whole, before being mounted in the vacuum vessel. In some respects, even this structure of a traveling wave tube does no longer fully meet the requirements for very short waves, because the double ceramic cage requires a relatively great diameter of the tube, which, it is true, is advantageous with tubes for relatively longer waves, but which, on the other hand, with tubes for very short waves, for instance within the range of about 4 cm., may require a disadvantageously high precision of the single structural parts. In order to prevent said difficulties concerning the helix support, there has been proposed a new method according to which the helix line, in spite of its favorable electrical properties, may be dispensed with. Instead of said helix line, a metallic block, provided with longitudinal and transversal slots, is used as a delay line, whereby said block does not require any special supporting means. In order to achieve, with said metallic block

2

being provided with longitudinal and transversal slots, quite handy dimensions, so-called spatial harmonics have been used for operating the tube, said spatial harmonics, as well known, occurring with delay lines having a periodical structure. Such a type of tube has for instance been described on the pages 1035 to 1043 of "Proc. of the I. R. E.," 1951.

It is the object of the invention, even for the operation with very short electro-magnetic waves, to provide traveling wave tubes having helix-shaped delay lines, whereby the difficulties, arising above all in this frequency range, such as the alignment of the electron beam axis with respect to the helix line axis, shall be overcome.

The invention is hereby based on the well known method of supporting a helix line wherein said helix line is embedded between several rod-like supports of insulating material, such as ceramic, quartz, or glass. For the purpose of adjusting the structure of the electrode system outside the tube envelope, said supports of the helix line are, in accordance with the invention, fastened to a part of the electron gun system or of the electron catcher of the tube by soldering or cementing said part which serves as a structural base. That is why the cementing or soldering to the part, serving as a structural base, can be easily done with such a precision that the helix line will always be properly embedded between the rods. By using said part, serving as a structural base, i. e. by properly locating it to the above mentioned rod-like helix supports, it is at the same time assured that the electron gun will be located in the position desired, i. e. that the axis of the electron gun coincides with the axis of the helix line. It is recommended to choose the diameter of the helix support rods, in particular when using ceramic material, within the same range as that of the helix diameter, since hereby, on one hand, the necessary rigidness is ensured, and, on the other hand, an almost complete dispersionlessness is obtained, which is most advantageous with respect to the operation of the tube. While it is, when using a soldering joint without applying any special measures, in general not recommended to fit the rods into the structural base by means of a snug fit, the latter is applicable without any disadvantage, when cementing. The soldering may for instance be done as a butt soldering. But it is even possible to fasten the ends of the rods in the structural base by means of a solder or a well known cement suitable for the use in a vacuum, i. e., it is not fastened in a snug fit, said rods having diameters somewhat smaller than the diameter of the aperture or recess within said structural base.

Through the German Patent 887,848 it is already known to locate both the electron gun and the delay line within the structure of the tube with respect to one common part, but the therein described well known arrangements have not the essential feature of the invention, viz. the ceramic rods, serving as helix supports, are soldered to a part which serves as mounting base. Contrary to the design according to the invention, with the arrangements in accordance with the German patent specification 887,848, the single structural parts of the tube system do not form a structural unit which can previously be mounted and adjusted outside the vacuum vessel.

The following embodiments are to illustrate the invention:

Figure 1 is a schematic drawing showing a side view of a traveling wave tube according to the present invention, this figure including wave guide means for feeding into and out of the tube a signal to be amplified.

Figure 2 is a sectional view through the electron gun end and part of the delay line of a practical embodiment of a tube according to the present invention.

Figure 3 is a sectional view through a jig of the type used to assemble part of the elements of the embodiment of Figure 2.

Figure 4 is a sectional view through the electron catcher end and part of the delay line supports of a practical embodiment of a tube according to the present invention.

Fig. 1 shows a schematic diagram of a traveling wave tube according to the invention. With said embodiment the vacuum vessel of the tube consists of a metal cup 1 which contains the electron gun, and which is followed by a tubular cylinder 2 of insulating material, such as glass or ceramic material. Said tubular part 2 is tapered at the end adjacent to the metal cup 1 in order to reduce the lever effect at the joint, i. e. at the glass-to-metal seal or at the ceramic-to-metal seal, when introducing the tube in the amplifier. At its other end, said tubular part 2 is terminated by means of the electron collector 3. The feeding of the radio frequency waves is done by a schematically indicated wave guide 4 which may be connected to the metal cup 1 for instance through springy contacts 5, and which may be connected to the helix line through a quarter-wave length resonator 6. The coupling-out device 7, 8, 9, which likewise contains a wave guide, is designed in a similar way. For the purpose of avoiding a radiation of radio frequency waves along the helix line, the tubular part 2 of the vacuum vessel is surrounded by a metallic screen 10. The bundled guidance of the electron beam along its way through the helix line 11 is done by means of the coaxial magnetic field of a solenoid 12 which, however, may be replaced by a corresponding arrangement of permanent magnets or by electrostatic focussing means known per se. The helix line is embedded between three ceramic rods 13 only two of which are to be seen in Fig. 1. Said ceramic rods 13 are soldered to a metal part arranged within the metal cup 1, said metal part serving as a mounting base; whereas at their other ends they are merely axially guided in the collector 3. In the embodiment described, the ceramic rods 13 are soldered to the mounting base 15 at such reciprocal distances that the helix line 11 may be with sliding contact introduced between the rods. Thus, any damage to the helix line, such as the slightest bending of single windings, is practically prevented. The fitting of the helix will then be effected during the assembling of the structural unit by means of a clip 50 which slightly presses the ceramic rods 13 against the helix line 11. In the embodiment described, said clip 50 is arranged within the range of an attenuating device 14 to prevent any field disturbance on the helix line. It goes without saying that, instead of one clip, even several clips distributed along the overall length of the helix line, or other suitable devices, such as mica rings or ceramic disks, may be provided. The ceramic rods 13, however, may also be soldered to the mounting base as such reciprocal distances that the diameter of the inscribed circle, resulting from such distances, is equal to the diameter of the helix line, so that the ceramic rods are to be slightly bent off when introducing the helix. In this case, the clips 50 may be dispensed with, but even here it is useful providing at least one clip or any corresponding means if the rods shall be brought in a particularly uniform touch with the helix line. The attenuation device 14 consists in a spirally shaped graphite strip to be deposited on at least one of the rods 13, said strip serving to absorb the waves recurring from the output of the tube to its input. The design of said attenuation arrangement corresponds to that shown in Germany Patent 932,731. Therefrom results a particularly high degree of reflectionlessness with a short structural length, which in practice, especially with the embodiment of a traveling wave tube shown in Fig. 1, is most useful.

In Fig. 2 there are shown details of the construction of the cathode side of a traveling wave tube in accordance with the invention. Corresponding parts are denoted with the same reference numerals as those of Fig. 1. Within

the metal cup 1 of the arrangement of Fig. 2, there is arranged the electron gun which is contained in the interior of a further metal cup 15 which is here used as an accelerating electrode/or anode. Said metal part 15 is, at its front surface facing the helix, provided with recesses in which the ceramic rods 13 have been soldered by using a jig. As regards the solder, a silver solder may hereby in a well known way be used, which, after an appropriate preparation of the ends of the ceramic rods 13, results in a sufficiently good joint.

The soldering of the ceramic rods 13 to the mounting base 15 may for instance be done in the following way:

The mounting base 15 is—as shown in Fig. 3—slid over a soldering jig which has a cylindrical or tube-like projection 42 extending in the direction of the helix axis. Said projection 42 is surrounded by three guiding-rods 43 parallel to the axis, whereby only two of them are to be seen in Fig. 3. After sliding the mounting base 15 over the part 42, a rod-shaped jig 44, having the same direction as the helix line, is introduced in a centrical boring of the part 42. Thereupon, the ceramic rods 13, being exactly ground with respect to their diameter, are fitted in the recesses provided for the soldering joints in the bottom of the mounting base 15, said ceramic rods 13 being at the same time pressed, by means of springy clips 45, against two sections 46 of the rod-shaped jig 44, having a somewhat greater diameter. According to one of the two before mentioned embodiments, the diameter of said sections 46 has hereby been chosen such that the diameter of the inscribed circle between the ceramic rods, resulting from the diameter of said sections 46, is slightly greater than the outer diameter of the helix later on to be embedded between said ceramic rods 13. After said ceramic rods 13 have been fitted in the mounting base 15, and after the solder has at the same time been inserted, e. g., in the form of a solder ring, the upper part 47 of the jig is slid over the guiding rods 43, said part 47, by means of guiding borings, preventing a twisting of the ceramic rod cage from that side, at the same time slightly pressing the ceramic rods 13 against the mounting base 15. For the purpose of securing the cage, on its side adjacent to the mounting base, against any twisting, the position of the mounting base is fixed in the place 48 by means of a groove and a tongue. After that, the soldering can be done, e. g. in an inert gas atmosphere, by heating with the help of an induction loop 49 of a radio frequency soldering device. After the soldering process, the parts 44, 47 of the jig as well as the clips 45 are removed, whereafter the ceramic cage together with the mounting base can be used as a structural unit for the assembling of the electrode system.

Coming back to Fig. 2, further details of a tube in accordance with the invention are shown. The further parts of the electron gun, such as the cathode 16 and the Wehnelt electrode 17, are, by means of ceramic distance pieces 18 and 19, introduced in the metal part 15 serving as a mounting base. The metal part 15 is then closed by a further metal part 20, which in the embodiment is likewise cup-shaped, in a way that by means of both the distance pieces 18, 19 and said part 20, the electrodes 15 and 16 of the electron gun are properly aligned with respect to the accelerating anode 15. The different electrodes of said electron gun are connected, over flexible conductors 21, 22, to the lead-ins 24 arranged in the sinter glass socket 23. Said sinter glass socket 23 is sealed to a further metal cup 1', so that there is obtained a complete structural unit consisting of the ceramic rods and the helix line system together with its coupling devices, and the electron gun contained in the mounting base 15.

Since the helix line together with its coupling devices 6, 7 is already to be embedded between the ceramic rods and adjusted, before introducing it in the vacuum vessel, it is recommended to provide the bottom of the metal cup 1 with such a big aperture that the before mentioned parts can be introduced in the interior of the tubular vacu-

um envelope 2 from the open end of the metal cup. In order to ensure that, during the operation of the tube, too much radio frequency energy can escape through said aperture, there is, in the embodiment of Fig. 2, additionally provided a hat-like metal part 26 which has already been assembled to the structural unit to be introduced in the vacuum vessel. In order to ensure that said hat-like part 26 does not change its position with respect to the bottom of the metal cup 1, the whole structural unit in the ready-assembled tube is pressed with its shoulder 29 against the bottom 30 of the metal cup 1 by means of a pressure spring 27 which at one of its ends engages the plate-like part 28 arranged within the part 1', and which at its other end engages the bottom of the part 20.

The electrical connection of the helix 11 with its coupling devices is, in the embodiment shown, effected such that the free end 33 of the helix line 11 is electrically connected to a tubular metallic projection of the hat-like part 26, for instance by means of spot welding or soldering, and such that said hat-like part 26 is electrically connected to the cup-like metal part 1 of the vacuum envelope, for instance by giving it an elastic property in the respective joining place. In order to insulate the metal cup 1 together with the helix line 11 from the mounting base 15 which at the same time serves as an accelerating anode, a distance plate 31 of insulating material is inserted between the two parts pressed together.

The vacuum tight joint between the parts 1 and 1' is usefully done by means of a so-called "concentrator soldering" 25 with the metal part 1' being so far slid into the metal cup 1 that the pressure spring 27 with a sufficient strength presses the electron gun against the bottom of the metal cup 1. Any lateral displacement of the electron gun during said process, firstly, by making the shoulder 29 of the cup bottom sufficiently large, and secondly, by providing an axial guidance of the ceramic rods 13 in the hat-like part 26. With the embodiment of Fig. 2, there is provided an additional ceramic guiding axis 32 which at one of its ends is fixed in the metal cup 20 closing the mounting base 15, and which at its other end is axially guided in the metallic disk 28 of the part 1. Taking into consideration the small diameter of the whole tube, which for instance corresponds to the dimensions shown in Fig. 1 at the scale of 1:1, it is furthermore recommended to use, as socket for the tube, a so-called "pico-socket," since said socket can be directly sealed to the metal part 1', which ensures simple manufacturing.

The dimensions of the essential structural parts of an embodiment of an arrangement according to the invention, i. e. the diameter of the helix line system together with its coupling devices, the diameter of the electron gun, etc., are furthermore usefully to be chosen such that there is a sufficiently great distance between the vacuum envelope and said structural parts, so that merely the central position, within the bottom 30 of the cup, of the before mentioned structural unit, consisting of the electron gun and the helix line system together with its coupling devices, is determined by the hat-like part 26 by means of the guiding borings for the ceramic rods 13. This is obtained by the fact, as is to be seen from Fig. 2, that the dilatation of the structural unit is possible in two directions, one of which refers to the ceramic rods and extends towards the electron catcher, and the other one of which refers to the electron gun and extends toward the socket side of the metal cup 1. As already shown in Fig. 1, the ceramic rods 13 are for this reason at the catcher-side end of the tube only guided in axial direction.

Fig. 4 shows the details of an embodiment for said design according to the invention. The tubular section 2 of the vacuum vessel, which may for instance consist of glass, is sealed to a shoulder of a cup-like metal part 34. Thus, the approximately equal diameters for the tubular

vacuum envelope 2 and for the cup-like metal part 34 may easily be realized. The three ceramic rods 13 rest in borings provided in the cup-like part, whereby said borings are to be recognized at the lower end of the drawing. 5 As to their length, the rods are dimensioned such that they have a certain play in the axial direction of the tube, whereby it is ensured that they cannot hit the electron catcher 35 itself. The electron catcher 35 itself is provided with a tubular cylindrical part 37 made of metal, 10 said part 37 being vacuum tightly sealed to a corresponding cylindrical part 36 of the metal cup 34 by means of a sinter glass seal 38. The tubular inserts 36, 37 are vacuum tightly joined to their respective parts by means of soldering. Since the design of the exhaust tube is 15 made similar to that of well known constructions of traveling wave tubes of this kind, it is not fully shown in Fig. 4. At the upper end of the metal cup 34 engaging the ceramic rods, there is again arranged a metal hat 40 to 20 which the free end of the helix line not shown in Fig. 4 is to be conductively connected, by spot welding or soldering, similar to the arrangement shown in Fig. 2.

The before mentioned embodiment is to illustrate that with the construction of the electrode system according to the invention it is possible to assemble the helix system, 25 including its coupling devices, and the electron gun to become a rigid structural unit by means of a metal-to-ceramic soldering, which can be easily made with high precision, even with very small dimensions of the helix line and the different structural parts. Thereby it is possible 30 to properly align said parts already outside the vacuum vessel, and thereupon to insert them in an exactly predetermined way into said vacuum vessel. Any mechanical stresses inside the vacuum vessel, which may for instance occur with the well known arrangement described in Fig. 35 1 of the above French patent specification 954,964, are thereby entirely prevented.

The embodiment of the invention shown in Fig. 1 to Fig. 4 is above all suitable for tubes with which a cathode, being relatively big with respect to the diameter of the electron beam, is to be used. According to a further development of the invention, the construction may be realized such that part of the electron catcher of the traveling wave tube, e. g. the cup-like metal part 34, is used as a mounting base, and that the electron gun is directly fastened, e. g. by means of clips, to the other free ends of the ceramic rods 13. Instead of said clip or of a corresponding cement joint, even a further metal-to-ceramic soldering may, however, be used in this case, similar to the arrangement according to Fig. 2. In this case, however, it should be observed that the tube envelope has free space for dilatation in axial direction, independent of both the electron gun and the helix system together with its coupling devices, for the purposes of preventing undesired mechanical stresses. It is, therefore, useful designing the feeding conductor between the tube socket e. g. 23 in Fig. 2 and the electron gun to be flexible. The construction, having an electron gun which is directly built in between the ceramic rods 13, is above all suitable with tubes having a small cathode diameter, i. e. for so-called initial stages or low-noise tubes. In this case it is, moreover, easily possible to keep the diameter of the vacuum vessel at least approximately constant over its whole length, which, with traveling wave tube amplifiers, is often required for reasons of construction.

It goes without saying that the electrode system according to the invention is extremely advantageous with traveling wave tubes having helix lines of a very small diameter, i. e. with traveling wave tubes to be operated within the range of the shorter cm.-waves. However, the electrode system according to the invention may also be advantageously used with traveling wave tubes to be operated with somewhat longer waves, since said system, compared to other well known systems for said range, can be manufactured in a considerably simpler and more exact 70 75 way.

If a magnetic screening of the electron gun should be required for electron-optical reasons, this could be for instance obtained by making the metal cup 1 in Fig. 2, containing the electron gun, and/or the mounting base 15 in Fig. 2 of magnetically screening material, e. g. of iron or Kovar.

We claim:

1. A traveling wave tube comprising a vacuum envelope; an electron gun sub-assembly; an electron catcher sub-assembly; a delay line including an elongated helix disposed between said sub-assemblies in the assembled traveling wave tube; and a delay line supporting cage including a plurality of rods of insulating material, said rods being disposed parallel to the axis of the helix and touching the outer periphery thereof; the rods at one end of the cage being all rigidly fixed to one of said sub-assemblies to axially align the helix therewith, and the other sub-assembly being rigidly fixed to said envelope and having rod guide means for slidably receiving the rods at the other end of said cage and supporting them transversely of said axis, the envelope having abutment and centering means for receiving said one of said sub-assemblies and for supporting it in spaced axial alignment with said other sub-assembly, closure means for closing the envelope after insertion of said one of said sub-assemblies and delay line in axial alignment with said other sub-assembly, means operative between the envelope and said one of said sub-assemblies for maintaining the latter engaged in said abutment and centering means, and said one sub-assembly being the electron gun sub-assembly and comprising electron stream emitting means; and at least one anode electrode between said emitting means and said delay line, said anode electrode serving as a mounting base to which said rods are directly attached.

2. In a tube as set forth in claim 1, said anode electrode being cup-shaped and opening away from said delay line, said rods being attached to the outer surface at the closed end of the electrode; insulated spacers insertable in said cup-shaped electrode and shaped to support said electron stream emitting means; and retaining means receivable within said cup-shaped electrode for securing said spacers and said emitting means therein.

3. In a tube as set forth in claim 1, said abutment and centering means being complementary in shape with at least a portion of said anode electrode, and said means operative between said envelope and said one sub-assembly comprising spring means compressed against said anode electrode and urging it toward said electron catcher.

4. In a tube as set forth in claim 3, an insulator disposed between said anode electrode and said abutment and centering means.

5. A traveling wave tube comprising a vacuum envelope; an electron gun sub-assembly; an electron catcher sub-assembly; a delay line including an elongated helix disposed between said sub-assemblies in the assembled traveling wave tube; and a delay line supporting cage including a plurality of rods of insulating material, said rods being disposed parallel to the axis of the helix and touching the outer periphery thereof; the rods at one end of the cage being all rigidly fixed to one of said sub-assemblies to axially align the helix therewith, and the other sub-assembly being rigidly fixed to said envelope and having rod guide means for slidably receiving the rods at the other end of said cage and supporting them transversely of said axis, the envelope having abutment and centering means for receiving said one of said sub-assemblies and for supporting it in spaced axial alignment with said other sub-assembly, closure means for closing the envelope after insertion of said one of said sub-assemblies and delay line in axial alignment with said other sub-assembly, means operative between the envelope and said one of said sub-assemblies for maintaining the latter engaged in said abutment and centering

means, and said envelope comprising a vessel of insulating material closed at one end by said electron catcher sub-assembly and sealed at its other end to a metal sleeve, said abutment and centering means being located in the sleeve and said envelope closure means being fixed at the open end of the sleeve.

6. In a tube as set forth in claim 5, said closure means comprising an annular member of such diameter as to telescope into said open end of the sleeve and be sealed thereto, and said annular member carrying a plurality of connection pins, the latter being connected to the parts of the electron gun by flexible conductors.

7. In a tube as set forth in claim 6, said means operative between said envelope and said one sub-assembly comprising a spring compressed between the latter and the said annular member when telescoped into the open end of said sleeve.

8. A traveling wave tube comprising a vacuum envelope; an electron gun sub-assembly; an electron catcher sub-assembly; a delay line including an elongated helix disposed between said sub-assemblies in the assembled traveling wave tube; and a delay line supporting cage including a plurality of rods of insulating material, said rods being disposed parallel to the axis of the helix and touching the outer periphery thereof; the rods at one end of the cage being all rigidly fixed to one of said sub-assemblies to axially align the helix therewith, and the other sub-assembly being rigidly fixed to said envelope and having rod guide means for slidably receiving the rods at the other end of said cage and supporting them transversely of said axis, the envelope having abutment and centering means for receiving said one of said sub-assemblies and for supporting it in spaced axial alignment with said other sub-assembly, closure means for closing the envelope after insertion of said one of said sub-assemblies and delay line in axial alignment with said other sub-assembly, means operative between the envelope and said one of said sub-assemblies for maintaining the latter engaged in said abutment and centering means, and said envelope comprising a vessel of insulating material containing said electron catcher sub-assembly and containing said abutment and centering means in spaced axially aligned relation, and said catcher sub-assembly comprising a supporting plate connected with said vessel and having a guide portion disposed normal to said axis and having apertures to receive the rods at said other end of the cage, the rods being reciprocable in said apertures to allow for thermal expansion.

9. In a tube as set forth in claim 8, said supporting plate having an opening therethrough spaced equi-distant from said apertures; and a catcher electrode behind said plate and aligned with said opening.

10. A traveling wave tube comprising a vacuum envelope; an electron gun sub-assembly; an electron catcher sub-assembly; a delay line including an elongated helix disposed between said sub-assemblies in the assembled traveling wave tube; and a delay line supporting cage including a plurality of rods of insulating material, said rods being disposed parallel to the axis of the helix and touching the outer periphery thereof; the rods at one end of the cage being all rigidly fixed to one of said sub-assemblies to axially align the helix therewith, and the other sub-assembly being rigidly fixed to said envelope and having rod guide means for slidably receiving the rods at the other end of said cage and supporting them transversely of said axis, the envelope having abutment and centering means for receiving said one of said sub-assemblies and for supporting it in spaced axial alignment with said other sub-assembly, closure means for closing the envelope after insertion of said one of said sub-assemblies and delay line in axial alignment with said other sub-assembly, means operative between the envelope and said one of said sub-assemblies for maintaining the latter engaged in said abutment and centering

means, and cement disposed in the joints between said rods and said one sub-assembly.

11. A traveling wave tube comprising a vacuum envelope; an electron gun sub-assembly; an electron catcher sub-assembly; a delay line including an elongated helix disposed between said sub-assemblies in the assembled traveling wave tube; and a delay line supporting cage including a plurality of rods of insulating material, said rods being disposed parallel to the axis of the helix and touching the outer periphery thereof; the rods at one end of the cage being all rigidly fixed to one of said sub-assemblies to axially align the helix therewith, and the other sub-assembly being rigidly fixed to said envelope and having rod guide means for slidably receiving the rods at the other end of said cage and supporting them transversely of said axis, the envelope having abutment and centering means for receiving said one of said sub-

assemblies and for supporting it in spaced axial alignment with said other sub-assembly, closure means for closing the envelope after insertion of said one of said sub-assemblies and delay line in axial alignment with said other sub-assembly, means operative between the envelope and said one of said sub-assemblies for maintaining the latter engaged in said abutment and centering means, and solder disposed in the joints between said rods and said one sub-assembly.
